UNITED STATES PATENT OFFICE.

HENRY W. BUEHLER, SR., OF NEW YORK, N. Y.

DESIGN FOR A PINCUSHION AND RECEPTACLE.

No. 39,514.

Specification for Design.

Patented Sept. 8, 1908.

Application filed June 19, 1908. Serial No. 439,466. Term of patent 7 years.

To all whom it may concern:

Be it known that I, HENRY W. BUEHLER, Sr., a citizen of the United States, residing in the borough of Brooklyn, city of New York, county of Kings, State of New York, have invented a new, original, and ornamental Design for a Pincushion and Receptacle, of which the following is a specification, reference being had to the accompanying drawing, forming part thereof.

The drawing is a perspective view of a pincushion and receptacle showing my new design.

I claim:

The ornamental design for a pincushion and receptacle as shown.
